United States Patent

Des. 239,848
Patented May 11, 1976

239,848

GAME BOARD

Eric S. Wessborg, 500 Sunburst Drive,
Frankenmuth, Mich. 48734

Filed Jan. 14, 1974, Ser. No. 433,381

Term of patent 14 years

Int. Cl. D21—01

U.S. Cl. D34—5 SS

FIG. 1 is a perspective view of the design for a game board.

FIG. 2 is a top plan view of the design for a game board as seen in FIG. 1.

FIG. 3 is a side elevation view of the design for a game board as seen in FIGS. 1 and 2.

FIG. 4 is a cross section view of the design for a game board taken on the line 4—4 of FIG. 3.

I claim:

The ornamental design for a game board, as shown.
